(57) **CLAIM**

The ornamental design for a dog cage, as shown and described.

DESCRIPTION

FIG. 1 is a first perspective view of a dog cage showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion in FIG. 1; and,

FIG. 10 is an enlarged view of the selected portion in FIG. 2.

The broken lines shown in the drawings depict portions of the dog cage in which the design is embodied that form no part of the claimed design.

The dot-dash line enclosing the enlarged portions are for depicting the boundary of the enlarged view and form no part of the claimed design.
